SKELETON JAR CLOSURE

Thomas L. Taliaferro, Chicago, Ill., assignor to
 Phoenix Metal Cap Company, Inc., Chicago,
 Ill., a corporation of New York

Application July 18, 1936, Serial No. 91,373

2 Claims. (Cl. 215—97)

The present invention relates to new and useful improvements in closures for containers and more particularly to improvements in a jar closing device.

5 An object of the invention is to provide a skeleton clamping device for securing the lid on a conventional Mason jar during the preserving process.

A further object of the invention is to provide 10 a device of the above type having a skeleton wire body portion to which is rigidly secured a convoluted wire thread which is adapted to follow the thread on the jar.

The above and other objects of the invention 15 will in part be obvious and will be hereinafter more fully set forth.

In the drawing:

Fig. 1 is a fragmentary side elevation showing the lid and clamping device in closed position on a jar.

20 Fig. 2 is an enlarged sectional view taken along the line 2—2 of Fig. 1.

Fig. 3 is a perspective view showing the skeleton clamping device in detail.

The present invention contemplates the use of a 25 skeleton wire clamping device which may be advantageously used in domestic preserving or canning. Heretofore, it has been customary to provide a conventional threaded cap for closing containers of the Mason jar type. In domestic canning with caps of this type, the caps are placed 30 on the jars rather loosely during the actual processing of the contents, after which the caps are screwed down tightly. In the above manner, there has always been the difficulty of removing the cap 35 from the jar due to the fact that some of the contents of the jar, particularly sticky syrup, brine or the like, overflows and hardens around the threads. According to the present invention, a substantially flat metal lid is provided for closing 40 the jar, and a skeleton clamping device having a wire thread is employed for holding the lid in position during the actual processing period. The clamping device may be turned to hold the lid in

45 position during the cooling of the jar, after which the clamping device is removed, and the vacuum incident to the cooling of the contents will hold the lid securely on the jar. With a skeleton clamping device of this character, there is little 50 or no possibility of the device becoming stuck to the jar because of any overflow during the processing period.

Referring more in detail to the accompanying drawing, a conventional Mason jar 10 is illustrated as being provided with a neck portion 11

having inclined threads 12 thereon. The lid 13 for closing the jar is preferably formed of metal in the form of a disc having an annular groove or channel 14 around the edge thereof and disposed directly over the edge of the neck portion 5 11 of the jar. A sealing composition 15 is placed within the annular groove 14 and forms a tight seal with the end of the neck portion 11 of the jar.

A skeleton clamping device 16, as shown in Fig. 3, is employed for securing the lid 13 on the jar 10 during the processing period. The clamping device, as illustrated, includes a pair of wire members 17, 18 which cross one another and are disposed at right angles to one another. The wire members 17, 18 are provided with central offset 10 portions 17a, 18a which are welded together, thus forming a skeleton body portion. The ends 17b, 18b of the crossed wire members 17, 18 respectively are turned downwardly. A wire 19 is formed 15 into a spiral with a pitch corresponding to the pitch of the threads 12 on the jar 10. The ends 19a, 19b of the wire 19 thus overlie one another and are spaced apart. The wire 19 is welded or otherwise rigidly secured to the depending ends 17b, 18b of the crossed wire members 17, 18 respectively. Both ends 19a, 19b of the wire 19 are secured to the depending end 17b of the wire 17. 20

In employing the jar closure of the present invention in domestic canning or preserving, the skeleton clamping device is screwed down on the 30 jar to loosely hold the lid in place during the actual steaming or processing period. After the jars are removed from the steaming device, the clamping device is turned to tightly hold the lid in place and the contents are allowed to cool. The cooling 35 creates a vacuum within the jar and thus holds the lid in place. After the jars have been cooled, the clamping device may be removed so that it can be repeatedly used, thus eliminating the necessity of having an individual band for each 40 jar. The skeleton band may of course be plated, as with chromium or the like, so that it will resist corrosion.

From the foregoing description, it is to be 45 clearly understood that minor changes in the details of construction and the arrangement of parts may be made without departing from the scope of the invention as set forth in the appended claims.

I claim:

1. A closure for jars comprising a lid, a gasket with which the lid is adapted to contact, and a clamping member for securing the lid on the jar including wire members extending across the lid 55

and having the ends thereof extending downwardly and a spirally wound wire secured to the downwardly extending ends of said wire members, said spirally wound wire being shaped to engage and follow threads on the jar whereby to hold the lid in place.

5. A closure for jars comprising a lid, a gasket with which the lid is adapted to contact, and a clamping device for securing the lid on the jar

including a plurality of crossed wire members extending across the lid and having the ends thereof extending downwardly and a spirally wound wire secured to and inside of the downwardly extending ends of said wire members, said spirally wound wire being shaped to engage and follow threads on the jar whereby to hold the lid in place.

5

THOMAS L. TALIAFERRO.
